UNITED STATES PATENT OFFICE.

MICHAEL B. STAZAK, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

TELEPHONE SYSTEM.

Application filed September 20, 1926, Serial No. 136,401. Renewed October 13, 1928.

My invention relates to telephone systems and has to do more particularly with common battery type systems in which the cord circuits used for interconnecting subscribers' lines are of the feature type, and an object of my invention is the provision of an improved circuit arrangement for a system of the above type.

One of the features of my invention is the provision of a telephone system in which the subscribers of an exchange system are divided into groups and terminate at the exchange in a group of finder switches as calling lines, and multiple jacks as called lines, and to which said lines are multiplied so that when a call is initiated one of the finder switches of the group is caused to operate to seize the contacts of the calling line.

Another feature of my invention is the provision of call distributing means in which a group of finder switches have multiply connected thereto cords terminating at the different operators' positions at the exchange switchboard, so that a group of subscribers' lines may, through the agency of this group of finder switches have access to a plurality of operators' positions so that the instant a subscriber initiates a call, he will be connected to anyone of the plurality of operators at the exchange board.

Another feature of my invention is the elimination of the answering jacks of the subscribers' lines terminating at the exchange board, the said lines being equipped with multiple jacks only thus permitting the lines per section to be materially increased.

Another feature of my invention is the means for controlling the busy indication at the operator's position. Each position remains busy so long as its particular operator has a greater number of calls before her than any other of the adjacent operators. Means are also provided for removing the busy indication whenever an operator has a smaller load, or a load equal to the smallest load on any operator's position.

Still another feature of my invention is a provision of distributing means whereby the calls are distributed among the different operators' positions to be stored and whereby as many as four calls may be stored at one position at one time, said distributing means operating in such a manner as to give each operator the same number of stored calls,

in case the operators are not keeping up with the load. This storing feature provides a definite means for checking up the speed at which the calls are being handled at any particular position.

Still another feature of my invention is the provision of a revertive tone which is connected to the sleeve of the jack of the calling line and serves as a revertive busy test on partly lines when a subscriber calling wishes to converse with another party on the same line. The revertive busy test gives the operator establishing the connection a tone which will indicate that the called party is on the same line as the calling party.

For a more complete understanding of my invention reference may be had to the accompanying drawings, in which I illustrate apparatus for interconnecting two subscribers, and which comprises Figs. 1, 2, 3, 4, 5 and 6, which, when joined as shown in Fig. 7, illustrate a complete connection.

Fig. 1 shows the calling line and finder switch, and a cord circuit finder switch,

Fig. 2 shows the cord circuit used for interconnecting the subscribers' lines,

Fig. 3 shows the busy control and call storing means,

Figs. 4 and 5 show the operator's sequence call selecting switches,

Fig. 6 shows an operator's circuit and selecting switch.

Referring now more in general to my invention as illustrated in Fig. 1 I show a calling substation A terminating at the exchange in a line circuit L comprising a line relay LR, 90 a cut off relay CO and multiple jacks J. The

finder switch FS of my invention comprises a motor magnet MM which automatically operates when a call is initiated by the subscriber at the substation A to step the wipers 95 2, 3, 4 and 5 over the bank contacts 6, 7, 8 and 9 to select the contacts of the calling line. A common starting wire 17 is provided which is common to a group of subscribers' lines which lead to a group of switches FS. A 100 bridging relay BG is provided which energizes when the calling line is seized by the switch FS to shunt the motor magnet MM to prevent further advancement of the wipers 2, 3, 4 and 5. The switching relay SW energizes upon the actuation of the relay BG to extend the starting conductor 17 through to the next finder switch FS of the group (not

shown). The switch FS is also provided with a release relay RE which when energized brings about the restoration of the switch wipers 2, 3, 4 and 5. A set of off normal contacts ON are provided which assume their alternate position on the first step of the switch wipers off normal and remains so until the switch FS is again restored to normal.

A group of cord circuit finder switches CFS are also associated with the group of calling lines and are similar to the switches FS and are provided with a spring restored shaft which carries wipers 54, 55, 56 and 57 and contacts 58, 59, 60 and 61 of which there are fifty sets, which may be engaged by the wipers 54, 55, 56 and 57, and to which contacts of the cord circuit C at the exchange are multipled. A motor magnet MM' is provided which steps the wipers 54, 55, 56 and 20 57 from one set of contacts 58, 59, 60 and 61 to the next in search of an idle cord circuit as C. A release magnet RE' is provided which when energized permits the release of the switch CFS allowing the wipers to restore. A set of off normal contacts ON' are provided which assume their alternate position upon the first step of the wipers off normal and again restore to their normal position when the wipers assume their normal 30 position when the switch is released.

The cord circuit C as illustrated in Fig. 2 is adapted to be seized by the finder switch CFS and terminates in the exchange switchboard in a calling plug CP. The cord circuit C is provided with a cord circuit battery feed relay CCR which is energized when the cord C is seized by the finder switch CFS and a relay 85 is provided which is actuated upon the energization of the relay CCR. An energizing circuit is also established for a busy control relay BCR to prepare circuits in the operator's busy control and storing circuits and in the operator's sequence selecting switch circuit, as will be more fully herein-after described. An operator's listening relay CLR is provided to control the connection of the operator's set O to the cord conductors of the cord C, and a calling lamp CAL is also provided which when lighted indicates to the operator associated with the cord C of which there are a plurality that a call has been extended to her position and to a particular cord C as will be described in detail when describing the detail operation of the circuits. A sleeve relay SL is provided which is energized when the calling plug CP is inserted into a jack of a called line, and a busy guard relay GU is energized upon the energization of the relay SL. A party line ringing key RK is provided and associated therewith are a plurality of ringing generators G, G', G² and G³ for the usual signaling purposes. A ringing control relay RCR, a ringing interrupter relay RI and a ringing trip relay RT are provided for controlling

the application of ringing currents to the called line, as will be more fully hereinafter described. A calling supervisory relay SR is also provided which is energized when the called subscriber answers. A combined disconnect and storing lamp signal DSL is provided for purposes as will be more fully hereinafter described.

In the system of my invention I divide the subscribers' lines of the exchange in groups of fifty each and I associate therewith from seven to ten finder switches FS so that each group of fifty lines may be equipped with an ultimate of ten trunks, this number of course depending upon the traffic of the group of lines to which the fifty lines are multipled. These trunks or cord circuit channels extend through cord circuit finder switches CFS which may have access to a maximum of fifty cord circuits as C. This group of fifty cords is multipled to as many more cord channels as will handle the traffic.

A group of one thousand lines would be separated into twenty units of fifty lines each and under average conditions each unit would be provided with seven cord channels with an ultimate provision of ten channels for each group. The twenty units of seven channels each will then have access to as many as fifty cord circuits or less depending upon the traffic. The cord circuits are arranged to be distributed to any of the operators' positions and in such a way that a position may have cord circuits from all of the groups for light traffic when only one or two operators are required at the board.

Referring now to Fig. 3 I illustrate three operator's busy control and storing circuits f, h and j assumed to be associated with three operators' positions F, H and J. Each circuit is similar to the others and a description of the circuit f of the position F is sufficient. The operator's busy control and storing circuit f is provided with four call storing relays CA, CA², CA⁶ and CA⁹ which are of the marginal type. The relay CA will operate through a 3000 ohm resistance to ground which is placed in circuit with the relay CA upon the energization of the relay BCR of a cord C which is seized to extend a connection to the operator's position F. The relay CA² will operate through a 1500 ohm resistance to ground, but not through 3000 ohms, relay CA⁶ through a 1000 ohm resistance to ground, but not through 1500 ohms, and relay CA⁹ through 750 ohms resistance to ground, but not through 1000 ohms, for the purpose of storing calls before this operator's position F, as will be more fully herein-after described. Busy clearing relays BC, BC³, BC⁶ and BC⁹ are also provided, which relays upon energization establish energizing circuits for the position busy relays PB, PB₂, PB₆ and PB₉, respectively, to establish energizing circuits for the group busy relays BU

which relays upon energization busy all the cords of the operator's position F when a cord has been seized in this operator's position.

5 Referring now to Figs. 4 and 5, I illustrate the operator's sequence call selecting switches SCS, SCS', SCS² and SCS³ which are provided four per operator. These switches, when calls are extended to the operator's position F, are provided to select the selected cord circuit to operatively connect therewith. When calls are stored at an operator's position as F, the switches SCS, etc., are operated and restored in regular rotation. The switch SCS which is typical of 10 all four switches with which each operator's position is equipped, will be described. It is provided with wipers 129, 130, 131 and 132 which through the agency of a motor magnet MM² are stepped into engagement with the contact sets 133, 134, 135 and 136 to select the contacts to which the seized cord circuit is multiplied. A bridging relay BG' is provided which when energized connects the operator's talking conductors to the cord conductors. A release magnet RM² is also provided, which when energized withdraws its retaining pawl to permit the wipers to restore to normal under spring tension. Off 20 normal contacts ON² are also provided, which assume their alternate position upon the first step of the wipers off normal and are restored to their normal position upon the restoration of the wipers to normal.

30 35 In Fig. 6 I illustrate an operator's selecting switch OS which comprises wipers 170, 171, 172 and 173 which are stepped from one contact set 174, 175, 176 and 177 to the next through the agency of a motor magnet MM⁶ to pick up the calls extended to an operator's position in the order in which they are received or stored at an operator's position. A bridging relay BG⁶ is provided which, when energized, connects the operator's set O through to the cord conductors. The switch is a five point switch and when the wipers reach the fifth set of contacts a release magnet RM⁶ is energized to release the wipers so that they may again be stepped from one contact to the next to connect the operator's set O to the cord conductors. A set of off normal contacts ON⁶ are provided which are moved to their alternate position upon the first step of the wipers off normal and moved back to their normal position when the wipers are restored to normal.

40 45 50 55

The operators' busy control and storing circuits f, h and j provide means for controlling the "busy" when the operator's set and cord are automatically selected in one of these positions. A position remains busy so long as a particular operator has a greater load than any adjacent operator (one in the same group) and the "busy" is removed whenever the operator has a smaller load, or one

equal to the smallest load on any operator's position in the same group.

A storing feature is also provided whereby as many as four calls may be stored in front of each operator. In the cord circuit C as 70 described in connection with Fig. 2 a lamp CAL is lighted when a call is extended to the operator's position and indicates to the operator at all times the number of calls stored at her position. The switches SCS, SCS', SCS² and SCS³ of which there are four for each operator's position also operate when calls are connected to an operator's position, and when calls are stored the switches SCS, SCS', SCS² and SCS³ also 75 80 85 operate to store the calls on the four switches SCS, SCS', SCS² and SCS³ in their regular rotation. The operator's switch OS of which there is one for each position, picks up these calls in the sequence in which they are received and stored.

Having described in general the switches and apparatus comprising the circuit arrangement of my invention, I will now describe in detail the operation of the circuits 90 in establishing a connection between a calling and a called subscriber and also the operation of the storing and sequence selection circuit associated with my invention.

Assuming now that the subscriber at the 95 substation A initiates a call, the removal of the receiver at the substation closes an energizing circuit for the line relay LR of the line circuit L over the line conductors. The closure of alternate contact 10 of the line 100 relay LR closes an energizing circuit for the motor magnet MM of the finder switch FS traced from battery through the resistance 11, through the winding of the motor magnet MM, its normal contact 12, conductor 13, 105 normal contact 14 of off normal contacts ON, conductor 15, normal contact 16 of the switching relay SW, common starting conductor 17, to ground at alternate contact 10 of the line relay LR. The motor magnet 110 MM upon energization steps the wipers 2, 3, 4 and 5 of the switch FS into engagement with the first set of contacts 6, 7, 8 and 9. Upon the first step of the wipers 2, 3, 4 and 5 from their normal position, the off normal 115 contacts ON of the switch FS assume their alternate position, and the opening of normal contact 14 opens the initial energizing circuit of the motor magnet MM, but a substitute energizing circuit is now established for 120 the motor magnet MM upon the closure of its normal contact 12, traced from battery through the resistance 11, through the winding of motor magnet MM, its normal contact 12, conductor 13, alternate contact 14 of off 125 normal contacts ON, conductor 18, normal contact 19 of the switching relay SW, conductor 20, to ground at normal contact 21 of the bridging relay BG.

The magnet M energizing, steps the wipers 130

2, 3, 4 and 5 into engagement with the next set of contacts 6, 7, 8 and 9 and the opening of its normal contact 12, again allows the motor magnet MM to restore. The alternate closing and opening of normal contact 12 of the magnet MM causes the magnet MM to energize and deenergize, thus stepping the wipers 2, 3, 4 and 5 over contacts 6, 7, 8 and 9 in search of the calling line. The line relay LR upon energization also closes its alternate contact 22 placing a ground upon the switch contact 6 associated with the calling line A over conductor 23 and when the wiper 2 engages the grounded contact 6 associated with the calling line a circuit is closed for the bridging relay BG traced from ground at alternate contact 22 of line relay LR, conductor 23, contact 6, wiper 2, conductor 24, normal contact 25 of switching relay SW, conductor 26, normal contact 27 of relay BG, through the winding 28 of relay BG, conductor 29 to battery through the resistance 11. The low resistance path through the winding 28 of the relay BG shunts the magnet MM, preventing further actuation of the magnet MM and the relay BG upon energizing also opens its normal contact 21 to remove ground from the motor magnet MM.

The closing of alternate contact 21 of the relay BG upon its energization closes an energizing circuit for the switching relay SW traced from battery through the winding of relay SW, conductor 30 to ground at alternate contact 21 of relay BG. The switching relay SW upon energization closes a locking circuit for itself traced from battery through its winding, its alternate contact 31, conductor 32, to ground at alternate contact 33 of the off normal contacts ON which assumed their alternate position upon the first step of the wipers of the switch FS off normal. The closing of alternate contact 16 of the switching relay SW now extends the common starting wire 17 through the alternate contact 16 of the switching relay SW to the starting wire 17', which leads to the next switch of the group so that in the event that another subscriber of the group with which the calling subscriber A is associated initiates a call the next switch of the group will select this calling line. The opening of normal contact 25 of relay SW opens the initial energizing circuit of relay BG but a substitute circuit is established for the same as will presently be described.

The switch FS having seized the calling line an energizing circuit is established for the line relay LR' associated with the cord finder switch CFS traced from battery through its lower winding, conductor 34, normal contact 35 of the cut off relay CO' of the switch CFS, wiper 5, contact 9, through the calling substation A back through contact 8 and wiper 4, normal contact 36 of relay CO', conductor 37 to ground through the upper winding of relay LR'. The relay LR' upon energization closes its alternate contact 38 to close the substitute circuit for relay BG which may be traced from battery through the resistance 11, conductor 29, the upper winding 28 of relay BG, the alternate contact 39 of relay BG, conductors 40 and 41, alternate contact 38 of relay LR', conductors 42 and 43, through the lower winding 44 of relay BG, conductor 45, wiper 3, contact 7, conductor 46 to ground through the winding of the cut off relay CO of the line circuit L. The cut off relay CO of the line circuit L operates over the circuit just traced and opens the energizing circuit of the line relay LR of the line circuit L which restores to normal. The relay LR' of the switch CFS energizing closes its alternate contact 47 to establish an energizing circuit for the control relay CR traced from battery through the winding of relay CR, conductor 48, normal contact 49 of the motor magnet MM' of the switch CFS, conductor 50, normal contact 51 of off normal contacts ON', conductor 52 to ground at alternate contact 47 of relay LR'. The relay CR upon energization closes its alternate contact 53, establishing an energizing circuit for the motor magnet MM' of the switch CFS traced from battery through the winding of magnet MM', conductor 62, alternate contact 53 or relay CR, conductor 63, through the winding of slow acting relay 64, conductor 65, normal contact 66 of relay 67, conductor 68, normal contact 69 of relay CO', conductor 70 to ground at wiper 55. The motor magnet MM' energizes over this circuit and steps the wipers 54, 55, 56 and 57 into engagement with the first set of contacts 58, 59, 60 and 61 which lead to a cord circuit as at the main exchange.

The motor magnet MM' upon energization opens its normal contact 49 to open the energizing circuit of the control relay CR and the relay CR now deenergizes, and the opening of its alternate contact 53 opens the circuit of the motor magnet MM'. Should the first set of contacts engaged by the wipers 54, 55, 56 and 57 lead to a cord circuit already in use, the private contact 59, now engaged by the wiper 55 will be grounded by instrumentalities more fully hereinafter described and another energizing circuit is established for the control relay CR, traced from battery through the relay CR, normal contact 49 of the magnet MM', alternate contact 51 of off normal contacts ON', which assumed their off normal position upon the first step of the wipers 54, 55, 56 and 57 from their normal position, conductors 71 and 63, through relay 64, conductor 65, normal contact 66 of relay 67, conductor 68, normal contact 69 of relay CO', conductor 70, wiper 55 to the grounded busy contact 59. The relay CR energizing closes its alternate contact 53 establishing an energizing circuit for the motor magnet MM' to ground at the busy

grounded contact 59 over the previously described path and the motor magnet MM' again energizes to step the wipers 54, 55, 56 and 57 into engagement with the next 5 set of contacts 58, 59, 60 and 61. The motor magnet MM' upon energizing opens its normal contact 49 allowing relay CR to restore and relay CR restoring in turn opens the circuit of the motor magnet MM' at its 10 alternate contact 53. It will thus be seen that due to the see-saw action of the relay CR and the motor magnet MM' the wipers 54, 55, 56 and 57 are stepped from one contact set to the next until an idle set is 15 encountered. When the wiper 55 engages an ungrounded contact 59 no energizing circuit is closed for relay CR and the relay CR remains at normal and prevents further actuation of the motor magnet MM' 20 and the wipers now remain in engagement with the idle set of contacts 58, 59, 60 and 61. The relay 64 remains energized during the rapid interruptions of the relay CR and its normal contact 72 remains 25 open during the selecting operation to prevent the operation of the cut off relay CO'. When the wipers engage an idle contact set the relay 64 restores and the closing of its normal contact 72 closes a circuit for the cut 30 off relay CO', traced from battery through the winding of relay CO', conductor 73, normal contact 74 of relay 67, conductor 75, normal contact 72 of relay 64, conductor 76 to ground at alternate contact 77 of off normal contacts ON'. 35

The closing of alternate contact 78 of relay CO' establishes an energizing circuit for relay 67 traced from battery through the winding of relay 67, conductor 79, alternate 40 contact 78 of relay CO', conductor 76 to ground at alternate contact 77 of off normal contacts ON'. The closing of alternate contact 80 of relay 67 establishes a locking circuit for itself traced from battery through the winding of relay 67, its alternate contact 45 80, conductors 81 and 76 to ground at alternate contact 77 of off normal contacts ON'. The initial energizing circuit of cut off relay CO' is opened at normal contact 74 of 50 relay 67, but a substitute energizing circuit is established for the cut off relay CO' before it has time to deenergize, as will be presently described. The closing of alternate contact 69 of relay CO' places ground 55 upon the private wiper 55 which busies the engaged contact 59 to prevent any other switch from engaging the selected contact set. The relay CO' energizing opens its normal contacts 35 and 36 thus opening the 60 energizing circuit of the line relay LR' and the relay LR' restores and its alternate contact 38 is opened to open the series circuit of the relay BG of the switch FS and the cut off relay CO of the line circuit L but the 65 closure of alternate contact 82 of relay 67

maintains relays BG and CO energized through the now closed contact 82 of relay 67.

The relay CO' upon energization closes its alternate contact 35 and 36 and extends the 70 calling line to the selected cord circuit C of Fig. 2 and an energizing circuit is now established for the cord battery feed relay CCR traced from battery through the lower winding of relay CCR, contact 61, wiper 57, 75 alternate contact 35 of relay CO', wiper 5, contact 9, through the calling substation A, back through contact 8 and wiper 4, alternate contact 36 of relay CO', wiper 56, contact 60, conductor 8 to ground through the upper 80 winding of relay CCR. The relay CCR upon energizing closes its alternate contact 84 thus establishing an energizing circuit for the relay 85 traced from battery through the winding of relay 85, conductors 86 and 87 85 to ground at alternate contact 84 of relay CCR. The relay 85 upon energization closes its alternate contact 88 connecting ground to the cut off relay CO' of the switch CFS which has remained energized momentarily due to its slow to release construction after 90 its initial energizing circuit is interrupted as before described and the substitute circuit for CO' may now be traced from battery through the relay CO', its alternate contact 95 89, conductor 90, wiper 54, contact 58, conductor 91 to ground at alternate contact 88 of relay 85, the said relay CO' remaining energized until the termination of conversation. 100

The closing of alternate contact 92 of relay 85 establishes a circuit for the combined disconnect and storing lamp DSL, traced from battery through the lamp DSL, alternate contact 92 of relay 85, conductor 93 to ground 105 at normal contact 94 of sleeve relay SL. The closing of alternate contact 95 of relay 85 establishes an energizing circuit for the busy control relay BCR of the seized cord circuit C, traced from battery through the winding 110 of relay BCR, conductor 96, alternate contact 95 of relay 85, conductor 97 to ground at normal contact 98 of the sleeve relay SL. The relay BCR energizing closes its alternate contact 99, establishing an energizing circuit 115 for the call storing relay CA of the operator's busy control and storing circuit F of Fig. 3, which circuit F is common to this operator's position F with which the cord circuit C as seized by the switch CFS is associated. The energizing circuit of the relay CA may be traced from ground through 3000 ohm resistance 100, alternate contact 99 of relay BCR, conductor 101 which is common to all relays BCR of cord circuits at the position 120 F, through the winding of relay CA, conductors 102 and 103, normal contact 104 of the busy clearing relay BC, conductors 105, 106 and 107, normal contact 108 of the busy clearing relay BC², conductors 109, 110, 111 to bat- 125 130

tery through normal contact 112 of busy clearing relay BC⁶. The relay CA upon energization closes its alternate contact 113 establishing an energizing circuit for the busy clearing relay BC, traced from battery through the winding of relay BC, to ground at alternate contact 113 of relay CA.

The relay BC upon energization closes its alternate contact 114 to establish an energizing circuit for the position busying relay PB, traced from battery through the upper winding 115 of relay PB to ground at alternate contact 114 of relay BC. The relay PB energizes over this circuit and closes its alternate contact 116 connecting ground to conductor 117, which ground operates the group busying relays BU which upon energization close their alternate contacts 118 temporarily busying the balance of the cords in this position by grounding the contacts 59 at the cord finder switches CFS, each cord having a wire 119 leading to a contact 118 of a busy relay BU. The busy potential thus placed on all the private contacts 59 and their multiples of cords at this operator's position remains connected until the call which has been extended over this selected channel to her position is extended to the called line, as will be more fully hereinafter described. The relay BCR upon energization also closes its alternate contacts 120 and 121. The closing of alternate contact 120 connects ground to the starting conductor SA common to all relays BCR of the position, to close an energizing circuit for the motor magnet MM² of the operator's sequence call selecting switch SCS, of which there are four for each operator's position, for purposes as will be hereinafter more fully described.

The circuit of the motor magnet MM² of the switch SCS may be traced from battery through the resistance 122, the winding of magnet MM², its normal contact 123, normal contact 124 of the off normal contacts ON², conductor 125, normal contact 126 of the switching relay SW', starting conductor SA, normal contact 127 of the cord listening relay CLR, conductor 128 to ground at alternate contact 120 of the relay BCR. The magnet MM² upon energization steps the wipers 129, 130, 131, 132 into engagement with the first set of contacts 133, 134, 135 and 136, and upon the first step of the wipers off normal, the off normal contacts ON² assume their alternate position, and the motor magnet MM² upon energization opens its normal contact 123 to interrupt its circuit and the magnet MM² now restores. The off normal contacts ON² having moved to their alternate position the initial energizing circuit of magnet MM² is opened at normal contact 124 of off normal contacts ON², but the closing of alternate contact 124 of off normal contacts ON² establishes a substitute energizing circuit for the motor magnet MM², traced from battery

through resistance 122, through the winding of the motor magnet MM², its normal contact 123, alternate contact 124 of off normal contact ON², conductor 137, normal contact 138 of relay SW', conductor 139, to ground at 70 normal contact 140 of the bridging relay BG'. The motor magnet MM² is again energized over this circuit, and, due to the opening and closing of its contact 123, it is thus alternately energized and deenergized to step 75 the wipers 129, 130, 131 and 132 from one set of contacts 133, 134, 135 and 136 to the next, and when the wiper 129 engages the contact 133 which was grounded upon the energization of the relay BCR of the cord circuit C, 80 an energizing circuit is established for the bridging relay BG' of the switch SCS which may be traced from battery through the resistance 122, conductor 141, through the upper winding 142 of the relay BG' normal contact 85 143 of relay BG', conductor 144, normal contact 145 of relay SW', conductor 146, wiper 129, contact 133, conductor 147, normal contact 148 of the relay CLR, conductor 149, to ground at alternate contact 121 of the relay 90 BCR. The relay BG' upon energization closes its alternate contact 150, closing a locking circuit for itself traced from battery through the resistance 122, conductor 141, through the upper winding 142 of the relay 95 BG', its alternate contact 150, lower winding 151 of the relay BG' conductor 152, wiper 130, contact 134, conductor 153, through the winding of the relay CLR, conductor 154, to ground at alternate contact 155 of the relay 100 BCR. The relay CLR is also energized over this circuit for the purposes as will presently be described.

The circuit just described, which causes the energization of relay BG' shunts the motor 105 magnet MM² and prevents further actuations of the said magnet, and the wipers 129, 130, 131 and 132 remain in engagement with the selected set of contacts 133, 134, 135 and 136. The relay BG' upon energization closes its 110 alternate contact 140 thus establishing an energizing circuit for the relay SW' traced from battery through the winding of the relay SW', conductor 156 to ground at alternate contact 140 of the relay BG', and the relay 115 SW' energizing closes its alternate contact 157 establishing a locking circuit for itself traced from battery through its winding, its alternate contact 157 to ground at alternate contact 158 of the off normal contacts ON². The closing of alternate contacts 159 and 160 of the relay BG' established an energizing 120 circuit for the line relay LR³ associated with the switch SCS, traced from battery through the lower winding of the relay CCR, 125 associated with the cord circuit C, alternate contact 161 of the relay CLR, conductor 162, contact 136, wiper 132, alternate contact 160 of the relay BG' through the winding of the line relay LR³, alternate contact 159 of the 130

relay BG', wiper 131, contact 185, conductor 163, alternate contact 164, of the relay CLR, conductors 165 and 83 to ground through the upper winding of the relay CCR. The relay 5 LR³ energizing closes its alternate contact 166, establishing an energizing circuit for the starting relay SG, traced from battery through the winding of the relay SG to ground at alternate contact 166 of the relay 10 LR³. The relay SG upon energization closes its alternate contacts 167 and 168, and the closing of alternate contact 167 establishes an energizing circuit for the switching relay BG⁶ of the operator's selecting switch OS, 15 traced from ground at alternate contact 167 of the relay SG, conductor 169, contact 175, wiper 171, conductor 178, normal contact 179 of relay 180, normal contact 181 of the relay BG⁶, through the low resistance winding 182 20 of the relay BG⁶, conductor 183, through the resistance 184 to battery.

The circuit just traced through the relay BG⁶ shunts the magnet MM⁶ of the switch OS, due to the low resistance path through 25 winding 182 of relay BG⁶, and prevents the magnet MM⁶ from stepping the wipers 170, 171, 172 and 173 of the switch. The relay BG⁶ upon energization opens its normal contact 181 and a substitute circuit is established 30 for the said relay BG⁶, traced from battery through the resistance 184, conductor 183, through the windings 182 and 185 of the relay BG⁶, normal contact 179 of the relay 180 to ground at alternate contact 167 of the relay 35 SG over the previously described path.

The closing of alternate contacts 186 and 40 187 of the relay BG⁶ connects the operator's set O to the cord conductors of the cord circuit C, from alternate contact 186 of the relay BG⁶, the wiper 172, contact 176, conductor 188, alternate contact 159 of relay BG', wiper 45 181, contact 135, conductor 163, alternate contact 164 of the relay CLR, conductor 165 to the tip strand of the cord C and the other 50 lead from the operator's set O extends through alternate contact 187 of the relay BG', the wiper 173, contact 177, conductor 189, through alternate contact 160 of the relay BG', wiper 132, contact 136, conductor 162, alternate contact 161 of the relay CLR, 55 to the ring strand of the cord C.

Referring again to the switch SCS, the energization of relay SW' causes its alternate contact 145 to close to establish an energizing circuit for the relay 190 of the cord C, traced 60 from battery through the winding of the relay 180 of the switch OS, conductor 191, wiper 170, contact 174, conductor 192, alternate contact 145 of the relay SW', conductor 146, wiper 129, contact 133, conductor 147, alternate contact 148 of the relay CLR to ground 65 through the winding of the relay 190 which relay energizes over this circuit, but relay 180 of the switch OS does not energize due to the high resistance of relay 190 of cord C.

The closing of alternate contact 193 of the relay 190 closes a circuit for the call lamp CAL traced from battery through the lamp CAL to ground at alternate contact 193 of the relay 70 190, and the lighting of the lamp CAL notifies the operator at the position F that the call has been extended to her position and is awaiting her attention. The operator's set O having been connected to the cord conductors, as just described through alternate 75 contacts 161 and 164 of relay CLR of the seized cord C, the operator, noting the lighted signal CAL, inquires the wants of the calling subscriber at substation A and assuming that it is the subscriber at the substation D 80 that is wanted, the operator associated with the seized cord C now tests the multiple jack J' of the wanted substation D as to its idle or busy condition in the usual manner by touching the tip of the calling plug CP to 85 the sleeve of the jack J' of the wanted line. If the said called line is busy the relay 400 in the operator's set O operates over a circuit traced from battery on the sleeve of the jack J' of the busy called line D, the tip of the 90 plug CP, normal contact 244 of relay SL, conductor 401, normal contact 402 of relay 228, conductor 403 to ground through the winding of relay 400.

Should the calling substation call a party 95 connected to the same line, I provide a special revertive busy tone which is transmitted to the operator testing the called line to indicate such condition. Assuming that such is the case now when the operator tests the called 100 line by placing the tip of the plug CP to the sleeve of the multiple jack of the called line the relay 400 of the operator's set operates over a circuit as previously described and from the description just given it is seen 105 that the relay 400 operates in either case. The closure of alternate contact 404 of relay 400 connects the special busy tone BO through alternate contact 194 of relay 190, (which relay 190 energized when the operator's set O was connected to the conductor of the cord circuit C as previously described) conductors 195 and 196, alternate contact 88 of relay 85, conductor 91, contact 58, wiper 54, conductor 90, condenser 197, conductor 45, wiper 3, contact 7, conductor 46 110 to the sleeve of the multiple jack J of the calling line. This tone which is placed upon the sleeve of the multiple jack of the calling line and which is now being tested by the operator extends through the tip of the plug CP which was placed to the sleeve of the multiple jack of the wanted line back over conductor 403 to the operator's set O and gives the testing operator a distinctive signal 115 apprising her of the fact that the called line is connected to the same line as the calling line and the operator now asks the calling party to replace his receiver while the called subscriber is signalled. From the above de- 120 125 130

scription it is seen that when the operator tests a line other than one in which the called party is on the same line the relay operates and the tone BO is connected through its alternate contact 404 but this connection is only incidental as in this case the operator receives only the customary busy click in her head receiver, but in the event that the party wanted is on the same line as the calling party the revertive busy tone BO is transmitted through alternate contact 404 of relay 400 as already described.

Assuming that the line of the called subscriber at D is idle the operator associated with the seized cord C inserts the calling plug CP of the cord C into the multiple jack J' of the wanted substation D, thus establishing a series energizing circuit for the sleeve relay SL and the cut off relay CO³ traced from battery through the windings 200 and 201 of relay SL, conductor 202, normal contact 203 of relay 228, conductor 205, sleeve contacts of the connected plug CP and jack J' to ground through the cut off relay CO³. The relay SL upon energization closes its alternate contact 206 thus establishing a locking circuit for itself traced from battery through the winding 200 of relay SL, its alternate contact 206, conductor 202 to ground through the cut off relay CO³ over the previously described path. The relay SL upon energization opens its normal contact 94 thus interrupting the initial energizing circuit of the combined disconnect and storing lamp DSL, but a substitute circuit is established for the lamp DSL which may be traced from battery through the lamp DSL, conductor 232, normal contact 233 of relay 228, conductor 234, normal contact 229 of relay RCR, conductors 230 and 222, normal contact 223 of relay RT, conductor 224, normal contact 225 of relay SR, conductor 226, normal contact 227 of relay 228, conductor 208 to ground at alternate contact 94 of relay SL, the said lamp remaining lighted until the operator depresses the ringing key RK to signal the called subscriber. The sleeve relay SL energizing closes its alternate contact 94 thus establishing an energizing circuit for the busy guard relay GU traced from battery through the winding of relay GU, conductors 207 and 208 to ground at alternate contact 94 of relay SL, for purposes as will presently be described.

The opening of normal contact 98 of relay SL opens the energizing circuit of the relay BCR, and the relay BCR upon deenergization opens its alternate contact 99. The opening of alternate contact 99 of relay BCR opens the energizing circuit of relay CA of the cord operator's control and storing circuit CSC associated with this operator's position F of which the cord C is one. The relay CA now restores and the opening of its alternate contact 113 opens the energizing circuit

of relay BC and the relay BC upon restoration opens its alternate contact 114, to open the energizing circuit of the relay PB. The relay PB upon deenergization opens its alternate contact 116, to remove ground from the group busying relays BU, which relays now restore. The opening of their alternate contacts 118 removes the busying grounds from the multiple contacts 59 of the switches CFS in which the cord C of the operator's position F terminates making them again selectable so that other calls may be extended to this operator's position F.

The closing of alternate contact 209 of the relay GU however places a busy potential upon the private contact 59 of the selected cord C which may be traced from ground at alternate contact 209 of relay GU, conductors 210 and 211 to the private contact 59, thus preventing any other switch CFS from selecting this particular cord that is now in use. The relay BCR upon restoration opens its alternate contact 155 to open the energizing circuit of the cord listening relay CLR of the cord C, and the relay BG' of the switch SCS. The relay CLR upon restoration opens its alternate contact 148, allowing relay 190 to restore and the relay 190 restoring its alternate contact 193 is opened to efface the call signal lamp CAL, and the opening of alternate contact 194 of relay 190 opens the tone contact from the sleeve of the jack of the calling line. The relay CLR upon restoration also opens its alternate contacts 161 and 164 to disconnect the operator's set O from the cord conductors. The relay BG' upon restoration closes its normal contact 140 closing an energizing circuit for the release magnet RM² of the switch SCS traced from battery through the winding of the release magnet RM², conductors 212 and 213, alternate contact 138 of relay SW', conductor 139 to ground at normal contact 140 of relay BG' and the release magnet RM² now withdraws the retaining pawl from the ratchet and allows the wipers 129, 130, 131 and 132 to restore to their normal position.

The relay 214 is also energized upon the restoration of the relay BG', due to the closing of its normal contact 140 but the energization of this relay has no effect on the circuit at this time. When the wipers reach their normal position the off normal contacts ON² assume their normal position, and the opening of alternate contact 158 of the said off normal contacts ON² opens the locking circuit of relay SW', and the opening of alternate contact 140 allows relay SW' to restore, and the opening of alternate contact 138 of relay SW' opens the circuit of the release magnet RM² and the relay 214 which relay and magnet now restore to normal. When relay BG' deenergizes, its alternate contacts 159 and 160 are opened allowing relay LR³ to restore and the relay LR³ in

turn opens the energizing circuit of the relay SG at its contact 166. The relay SG upon deenergization opens its alternate contact 167 thus opening the energizing circuit of relay BG⁶ of the switch OS, and the relay now restores. The sequence selecting switch SCS and the operator's selecting switch OS are now at normal and are again ready to select another call that may be extended to the operator's position F.

Returning now to the point where the operator has inserted the calling plug CP of the cord C into the jack J' of the called line the operator associated with the cord C now depresses the proper ringing key plunger of the ringing key RK to connect the proper ringer generator frequency of the generators G, G', G², or G³, as the case may be, to operate the call signal at the called substation D.

Assuming that the ringing generator G' is the proper frequency for signalling the substation D, the operator depresses the ringing key plunger associated with this frequency, and the depression of the said key plunger actuates the end spring 220 causing it to momentarily assume its alternate position, and the closure of the said contact 220 establishes an energizing circuit for the ringing control relay RCR, traced from battery through the winding of relay RCR, conductor 221, alternate contact 220 of the end springs, conductor 222, normal contact 223 of the ringing trip relay RT, conductor 224, normal contact 225 of the supervisory relay SR, conductor 226, normal contact 227 of relay 228, conductor 208 to ground at alternate contact 94 of relay SL. The closing of alternate contact 229 of relay RCR establishes a locking circuit for itself traced from battery through the winding of relay RCR its alternate contact 229, conductors 230 and 222 to ground at alternate contact 94 of relay SL over the previously described path independent of the end spring contact 220. The relay RCR upon energization opens its normal contact 229 to bring about the effacement of the lamp DSL and the closing of its alternate contact 236 establishes an energizing circuit for the ringing interrupter relay RI traced from battery through the winding of relay RI, alternate contact 236 of relay RCR, conductor 237 to ground at alternate contact 238 of the end springs.

The relay RI is energized over this circuit the instant that the key plunger of the selected ringing frequency is depressed which also actuates the end springs to give the subscriber at the called substation an instantaneous first ring as will now be described. The instant that the relay RI is energized ringing current from the generator G' is impressed on the called line traced from the ungrounded pole of the generator G' through the closed contact of the ringing key plunger, conductor

239, through the winding 240 of the ringing trip relay RT, conductor 241, alternate contact 242 of the relay RI, conductor 243, alternate contact 244 of the sleeve relay SL, tip contacts of the connected plug CP and jack J' through the call bell and condenser at the called substation D, back through the ring contacts of the connected jack J' and plug CP, alternate contact 245 of the relay SL, conductor 246 to battery and ground at alternate contact 247 of the relay RI. The flow of current from the generator G' over the path just described gives the called subscriber at the substation D an instantaneous first ring.

When pressure is released from the key plunger of the selected frequency the end springs assume their normal position and the opening of alternate contact 238 opens the initial circuit through relay RI but the closing of normal contact 238 of the end springs now connects the constantly rotating interrupter I in the circuit with the relay RI through alternate contact 236 of relay RCR. The relay RI is intermittently energized and deenergized by the interrupter I and the ringing current from the generator G' is thus connected and disconnected over the path previously described to intermittently operate the call signal at the called substation D. The closing of alternate contact 248 of the relay RI also connects current from the generator G³ over conductor 249, through alternate contact 248 and conductor 250 to the tip conductor of the cord C and back to the calling subscriber at the substation A to give the subscriber thereat an audible revertive ringing tone which is an indication that the called subscriber is being signalled.

The subscriber at the called substation in response to the call signal removes his receiver from the switchhook and should the subscriber at called substation D remove his receiver during a silent period the supervisory relay SR is energized over a circuit traced from battery through the lower winding of relay SR, conductor 251, normal contact 247 of relay RI (which is in a deenergized position during a silent period) conductor 246, alternate contact 245 of relay SL, ring contacts of the connected plug CP and jack J', through the closed contacts of the substation switchhook at substation D, back through the tip contacts of the connected jack J' and plug CP, alternate contact 244 of relay SL, conductor 243, normal contact 242 of relay RI, conductor 252, to ground through the upper winding of relay SR. The supervisory relay SR upon energization opens its normal contact 225 which opens the locking circuit of the ringing control relay RCR and the relay RCR upon deenergization closes its normal contacts 253 and 254 to extend the talking circuit to the called substation D. The opening

of alternate contact 236 of the relay RCR disconnects the interrupter I from the ringing interrupter relay RI and the said relay RI restoring prevents further application of ringing current.

Should the subscriber at the substation D remove his receiver during a ringing period, the combined generator and battery current flowing through the winding of the ringing trip relay RT, causes the same to actuate, and the opening of its normal contact 223 opens the locking circuit of the ringing control relay RCR, which relay restores, and the opening of its alternate contact 236 disconnects the interrupter I from the interrupter relay RI and the said relay RI now restores to normal and prevents further application of ringing current after the called subscriber at the substation D answers in response to his call signal.

The subscriber at the substation A and the subscriber at the substation D are now in conversational circuit, the talking circuit being traced over the heavily marked conductors.

Assuming now that the subscribers at the substations A and D have finished their conversation, they replace their receivers upon their respective switchhooks. The replacing of the receiver by the subscriber at the substation A opens the circuit of the relay CCR of the cord circuit C at the switchhook contacts and the closing of normal contact 84 of relay CCR establishes an energizing circuit for the relay 228 traced from battery through the winding of relay 228, conductor 255, alternate contact 256 of relay 85, conductor 257 to ground at normal contact 84 of relay CCR. The relay 85 deenergizes upon the deenergization of relay CCR due to the opening of alternate contact 84 but the relay 85 due to its slow to release construction holds up momentarily until relay 228 energizes.

The relay 228 upon energization closes its alternate contact 258 establishing an energizing circuit for the relay 259 traced from battery through the winding of relay 259, conductor 260, alternate contact 258 of relay 228, conductor 205, sleeve contacts of the connected plug CP and jack J' to ground through the winding of the cut off relay CO² of the line circuit L'. The relay 259 upon energization closes its alternate contact 261 establishing a locking circuit for the relay 228 traced from battery through the winding of relay 228, its alternate contact 227, conductors 208 and 262 to ground at alternate contact 261 of relay 259. The relay 228 upon energization opens its normal contact 203 which opens the initial energizing circuit of the relay SL but a substitute circuit is established for the relay SL traced from battery through the upper winding 200, its alternate contact 206, conductors 202 and 270, alternate contact 271 of relay SR, conductors 272 and 205, sleeve contacts of

the plug CP and jack J' to ground through the cut off relay CO², the said relay SL remaining energized until the called subscriber at D replaces his receiver.

The relay 85 having deenergized as before described opens its alternate contact 88 thereby removing ground from the conductor 91 which opens the locking circuit of the cut off relay CO² of the switch CFS and allows the relay CO² to restore. The relay CO² upon deenergization closes its normal contact 78 establishing an energizing circuit for the release magnet RE' of the switch CFS traced from battery through the winding of magnet RE', conductor 265, alternate contact 266 of relay 67, conductor 267, normal contact 78 of relay CO², conductor 76 to ground at alternate contact 77 of off normal contacts ON' of the switch CFS. The release magnet RE' upon energization removes the retaining pawl from the ratchet allowing the wipers 54, 55, 56 and 57 to restore to their normal position under spring tension. When the wipers have restored to normal, the off normal contacts ON' are moved to their normal position and the opening of alternate contact 77 of the off normal contacts ON' opens the locking circuit of the relay 67 which restores and the opening of alternate contact 266 of relay 67 opens the circuit of the release magnet RE' which restores to normal. The cord circuit finder switch CFS is now at normal.

The relay 67 deenergizing opens its alternate contact 82 which opens the locking circuit of the relay BG of the finder switch FS and the relay BG upon deenergizing closes its normal contact 21 establishing an energizing circuit for the release relay RE traced from battery through the winding of relay RE, conductor 268, alternate contact 269 of relay SW, conductor 20 to ground at normal contact 21 of relay BG. The release relay RE upon energization removes the retaining pawl from the ratchet allowing wipers 2, 3, 4 and 5 to restore to their normal position under spring tension. When the wipers have restored to normal the off normal contacts ON are restored to their normal position and the opening of alternate contact 33 of off normal contacts ON opens the locking circuit of the relay SW which restores and the opening of alternate contact 269 of relay SW opens the circuit of the release magnet RE which restores to normal. The opening of the locking circuit of the relay BG also opens the energizing circuit of the cut off relay CO of the line circuit L associated with the calling line A and the line circuit of the calling line A and the switch FS are now at normal and are available for extending other connections. The opening of the series energizing circuit of the relay CO and relay BG as before described removes the busy potential from con-

tact 7 engaged by wiper 3 and the sleeve contact of the multiple jacks J associated with the calling line A so that the said line is immediately available as a called line and also 5 allows the calling line to immediately recall.

- The replacing of the receiver at the called substation D opens the circuit of the supervisory relay SR of the cord C at the switch-hook contacts and the relay SR deenergizing 10 opens its alternate contact 271 allowing relay SL to restore. The relay SL upon deenergizing opens its alternate contacts 244 and 245 which opens the tip and ring conductors of the cord and as relay 259 is energized as before described to ground through the cut off relay CO³ the relay CO³ deenergizes due to the high resistance of relay 259 placing the line relay LR³ again under the control of the called substation D to permit the called 15 subscriber at D to recall before the plug CP is disconnected from the jack J'. The deenergization of relay SL closes its normal contact 94 closing a circuit for the combined disconnect and storing lamp DSL traced 20 from battery through the lamp DSL, conductor 232, alternate contact 233 of relay 228, conductors 273 and 93 to ground at normal contact 94 of relay SL. The lamp DSL is lighted over this circuit and signals the operator associated with the cord C that the 25 subscriber has finished the conversation. The relay SL upon deenergizing opens alternate contact 94 thus opening the energizing circuit of the relay GU but the relay GU is held energized to ground at alternate contact 261 of relay 259. The relay GU is thus 30 maintained energized and continues to connect ground to the test conductor 211 which leads to the test contacts 59 of the switch CFS to which the cord circuit is multiplied, thus any other finder switch CFS is prevented from selecting the cord C that is still 35 connected to the called line D. The operator noting the lighted disconnect signal DSL now withdraws the plug CP from the jack J' of the called line which allows relay 259 to deenergize. The relay 259 upon deenergizing opens its alternate contact 261 which allows relays GU and 228 to restore to normal. 40 The relay 228 upon deenergizing opens its alternate contact 233 to efface the signal DSL. The relay GU upon deenergization opens its alternate contact 209 removing ground from the test conductor 211, thus 45 removing the busy potential to render the cord C selectable by other switches CFS. The apparatus used in establishing the connection from the calling subscriber at substation A to the called subscriber at the substation D is now at normal and available for establishing other connections.

In the foregoing description we have assumed that all the apparatus was in its normal unactuated position, but for a clearer 50 understanding of the operator's busy control

and storing circuit of Fig. 3 and the operator's sequence selecting circuits of Figs. 4, 5 and 6, we will now describe more in detail the operation of the circuits when calls are being stored before the different operators' 70 positions illustrated in Fig. 3, and the method of selecting the calls in sequence by means of the operator's sequence selecting circuits, illustrated in Figs. 4, 5 and 6.

Assuming now that the operators at positions F, H and J are idle and that the first call coming in has selected the cord C associated with the operator's position F, as in the previous description, relays CCR, 85 and BCR are energized; and the closure of the alternate contact 99 of relay BCR of the selected cord C connects the 3000-ohm resistance 100 from ground to battery through the relay CA of the operator's position F over a path previously described. The relays BC⁸⁵ and PB are also operated as previously described and the relay PB closes its alternate contact 116 to cause the operation of the group busy relays BU which relays BU operate to place a ground or busy potential 90 upon the balance of the cords in this operator's position F, as previously described in detail.

Assuming that the operator at position F does not answer this call, the second call 95 extended to the exchange will select a cord as C in the operator's position H. Relays CCR, 85 and BCR of the cord C seized in the operator's position H will operate in a like manner, and the closing of alternate contact 100 99 of the relay BCR will connect ground through the 3000-ohm resistance through the winding of relay CA' of the operator's position H to battery at normal contact 112' of the relay BC' associated with the operator's 105 position H. Relay CA' operates to close an energizing circuit for the relay BC', due to the closure of alternate contact 113' of the relay CA'. The relay BC' energizing in turn establishes an energizing circuit for the relay PB' traced from ground through alternate contact 114' of the relay BC', and through the winding 115' of the relay PB' to battery. Relay PB' energizing its alternate contact 116' is closed to establish an energizing circuit 110 for the group busy relays BU associated with the operator's position H, which relays BU operating close their alternate contacts, placing a ground or busy potential 115 upon the rest of the cords in this position H. 120

Assuming that the operators at positions F and H do not answer either call and that a third call is initiated it is extended to the position J, the only position having cords not busy. The relay CA² associated with the 125 position J will operate from ground through the 3000-ohm resistance of the selected cord C of the operator's position J, through the winding of the relay CA² to battery at normal contact 112² of relay BC⁸ of the position 130

J. The closing of alternate contact 113² of relay CA² closes a circuit through relay BC², which will be energized to in turn close a circuit for the relay PB² traced from battery 5 through its upper winding 115² to ground at alternate contact 114² of relay BC². The closure of alternate contact 300² of relay BC² closes a circuit through the lower winding 301² of relay PB² traced from battery through 10 the winding 301², alternate contact 300², conductor 302, alternate contact 303² of the relay BC' of the position H, alternate contact 303 of the relay BC of the position F to ground. The closing of alternate contact 304² of the 15 relay BC² at the position J now closes a circuit through the lower winding 301' of the relay PB' of the position H, the circuit being traced from battery through the lower winding 301', alternate contact 300' of the relay BC', conductor 305, the alternate contact 306 of the relay BC of the position F, conductor 307, alternate contact 304² of relay BC² of position J to ground.

The closing of alternate contact 306² of the 20 relay BC² of the position J closes a circuit through the lower winding 301 of the relay PB of the position F, traced from battery through the winding 301, alternate contact 300 of the relay BC of the position F, conductor 308, alternate contact 306' of the relay BC' of the position H, conductor 309, alternate contact 306² of the relay BC² of the position J to ground. The circuits through the lower windings 301, 301', 301² of the relays 25 PB, PB' and PB² of the positions F, H and J bring about the de-energization of the said relays at the respective positions F, H and J, due to their differential construction, and the opening of their alternate contacts 116, 116' and 116² removes the ground from conductors 117, 117' and 117² to open the circuits of each of the groups of busy relays BU associated with the positions F, H and J, thus removing the busying ground from all the 30 cords in these positions not in use. Assuming that the operators at positions F, H and J have not answered any one of the three calls and a fourth call comes in, and assuming that position F is selected, the relay BCR of the seized cord circuit C associated with the position F that is extending the call to the operator's position F closes its alternate contact 35 99, placing an additional 3000-ohm resistance 100 in multiple with the common conductor 101, and the two 3000-ohm resistances 100 placed in multiple with the conductor 101 reduce the resistance to 1500 ohms, and as the relay CA³ will operate through 1500 ohms the relay CA³ of the position F operates over a 40 circuit traced from battery at normal contact 112 of the relay BC⁶, conductors 111, 110 and 109, normal contact 108 of the relay BC³, conductors 107 and 106 through the winding of the relay CA³, conductor 102, through the winding of the relay CA and over conductor 45

101 to ground at the alternate contacts 99 of the two relays BCR of the cord circuits C that are selected, now that another call has been extended to the operator's position F. The relay CA³ upon energization closes its alternate contact 113³ to bring about the energization of relay BC³, and the relay BC³ in turn closes a circuit for the relay PB³, and the relay PB³ upon energization closes its alternate contact 116³ to again establish an energizing circuit for the busy group relays BU associated with the position F, which relays upon energization again close their alternate contacts to busy the remaining cords at the operator's position F. 50

The fifth incoming call will be extended to position H and cause the energization of the relay CA⁴ associated with the position H, the said relay CA⁴ energizing in a similar manner to that described in connection with relay CA³ of position F, whereby two resistances 100 placed in multiple with the conductor 101 permit the relay CA⁴ to energize for the same reason as described in connection with relay CA³ of position F. The relay CA⁴ upon energization closes its alternate contact 113⁴ and brings about the energization of the relay BC⁴, which in turn closes a circuit for relay PB⁴, and the relay PB⁴ upon energization closes its alternate contact 116⁴ to operate the 95 busy group relays BU associated with the position H to cause the remaining cords at the position H to be busied against selection.

The sixth incoming call will be extended to the position J to cause the relay CA⁵ to be 100 energized in a manner obvious from the preceding explanation, and relay CA⁵ in turn brings about the energization of the relay BC⁵ through its alternate contact 113⁵. Relay BC⁵ upon energization closes its alternate contact 114⁵ to close a circuit through the upper winding of the relay PB⁵, but the relay PB⁵, due to the differential construction, restores to normal, as a circuit is also closed through its lower winding which 105 brings about the deenergization of this relay PB⁵. The differential relays PB³ and PB⁴ of the positions F and H also restore to normal due to circuits being closed through their lower windings over circuits corresponding to those described in connection with the first 110 three calls that were stored at the operators' positions F, H and J. The relays PB³, PB⁴ and PB⁵ open their alternate contacts to permit the de-energization of the busy group relays BU associated with the three positions F, H and J, and each group of relays BU associated with said position will cause the remaining cords in the positions F, H and J to again test idle. 115

Assuming that none of the six calls thus far extended to the positions F, H and J have been answered, a seventh call coming in will again be extended to the position F, and as 120 relays BC and BC³ of the position F are ener- 125 130

gized, the normal contacts 104 and 108 of the relays BC and BC³ are opened and such seventh call will be extended to a cord circuit C at the position F and bring about the 5 energization of the relay BCR at that cord, and the closing of its alternate contact 99 will place another 3000-ohm resistance 100 in multiple with the other two resistances 100 of the two other cords C that have been connect- 10 ed. The resistance between conductor 101 and ground being 1000 ohms relay CA⁶ energizes and brings about the energization of the relays BC⁶ and PB⁶. The relay PB⁶ energizing its alternate contact is closed to energize the group busy relays BU, which relays BU in turn busy the remaining cords at 15 the operator's position F.

An eighth call coming in will operate the relay CA⁷ in a like manner as described in 20 connection with relay CA⁶, and the relay CA⁷ upon energization brings about the energization of the relays BC⁷ and PB⁷, and the closing of the alternate contact of the relay PB⁷ operates the busy relays BU associated with 25 the position H, busy all the remaining cords of this operator's position.

A ninth call coming in will be extended to the operator's position J and cause the energization of the relay CA⁸ of position J in the 30 same manner as described in connection with relay CA⁶ and the relay CA⁸ in turn closes the circuits for the relay BC⁸ and the relay PB⁸. The relay PB⁸ will not energize due to a circuit now being closed through its up- 35 per and lower windings, which circuit is closed upon the energization of relay BC⁸, and due to the differential construction of the relay PB⁸ the relay remains at normal. Circuits are also established through the lower windings of the relays PB⁶ and PB⁷ of the 40 positions F and H upon the energization of relay BC⁸ of position J, and due to their differential construction they restore, and due to the opening of the alternate contacts of the 45 relays PB⁶ and PB⁷ and PB⁸ at the positions F, H and J, the circuits of each group of group busy relays BU will be opened and permit the deenergization of their associated 50 group busy relays BU to remove the busy from the remaining cords at the positions F, H and J.

A tenth call coming in will be extended to the operator's position F, and a cord circuit C having been seized in the operator's position F, a fourth 3000-ohm resistance 100 is connected in multiple with the other three resistances 100 of the other cords at the operator's position F to further reduce the resistance connected to the common conductor 101, 55 thus causing the relay CA⁹ to energize and the relay CA⁹ energizing brings about the energization of the relays BC⁹ and BP⁹, and the relay PB⁹ upon energization closes its alternate contact to energize the group busy- 60 ing relays BU associated with the position F.

to busy the remaining cords at the operator's position F.

An eleventh call coming in will be extended to the operator's position H, and the relay CA¹⁰ is energized in the same manner as 70 relay CA⁹, and the relay CA¹⁰ in turn will bring about the energization of the relays BC¹⁰ and PB¹⁰, and the relay PB¹⁰ in turn will bring about the energization of the group 75 busy relays BU associated with the position H to busy the remaining cords in this position.

A twelfth call coming in will be extended to the operator's position J and cause the energization of the relay CA¹¹ in the same manner as described in connection with relay CA⁹ and CA¹⁰, and the relay CA¹¹ upon energization will bring about the energization of the relay BC¹¹. No energizing circuit is effected for the relay PB¹¹ of the position J 80 as a circuit is also closed through its lower winding, and due to its differential construction relay PB¹¹ deenergizes. Relays PB⁹ and PB¹⁰ at the positions F and H are also deenergized due to the circuits being established 85 through the lower windings upon the energization of relay BC¹¹ of position J, and due to their differential construction they restore 90 to normal and the opening of their alternate contacts will permit the deenergization of the group of group busy relays BU of the 95 respective positions F, H and J, removing the busy from the remaining cords at the operators' positions.

For a simple understanding and description of the circuit operation, I have in the foregoing assumed that the calls came in to the various positions in regular sequence, that is, 1, 2, 3, order, top level, then 1, 2, 3 order, second level, and so on down to the bottom level. It is however, obvious that in actual practice such regular sequence would rarely, if ever, occur. Now that the regular order of operation is disclosed it is apparent that the organization of the system as a 100 whole assures merely the desired method of operation, which is that each operator of the group F, H and J, has one stored call (it making absolutely no difference in the circuit organization which of F or H or J got the 110 first call or the last call) before a second call 105 can be stored before any operator of the group. Furthermore, it is indifferent to the circuit organization whether the second call stored at one position happens to strike F, 115 H or J. The organization of circuits, however, does guarantee to each operator that she will not have a third call stored against her until the operators each have two awaiting attention. In other words, the calls will 120 in actual practice be stacked up at hazard, as one might say, except that no operator can ever have more than one call more than any other operator.

In the description thus far we have as- 125

sumed that twelve calls have come in and none of them were answered so that each of the positions F, H and J have four calls stored in each position.

5 Four cords C have been seized in each operator's position F, H and J, as just described, and from the previous description, it is remembered that relays CCR, 85 and BCR are energized as soon as switch CFS 10 seizes the cords C in the positions F, H and J. The energization of each of the relays 85 of the cord circuits C will bring about the lighting of the disconnect and storing lamps DSL and the glowing of the four lamps DSL 15 at each operator's position F, H and J shows that four calls are stored at each of the operator's positions. When the first call was stored in the operator's position F the relay BCR was energized, and the closure of its 20 alternate contact 120 of the relay BCR closes an energizing circuit for the motor magnet MM² of the sequence call-selecting switch SCS, of which there are four for each operator's position, and the motor magnet MM² 25 steps the wipers 129, 130, 131 and 132 into engagement with the set of contacts 133, 134, 135 and 136 which lead to the seized cord C. The second call stored at the position F causes the relay BCR of the second seized 30 cord C to close its alternate contact 120 to establish an energizing circuit for the motor magnet MM² of the switch SCS' associated with the operator's position F, the circuit being traced from battery through the 35 resistance 122', through the winding of the magnet MM², its normal contact 123', normal contact 124' of the off-normal contacts ON³, conductor 125', normal contact 126' of the relay SW², over conductor 315, through alternate contact 126 of relay SW² of switch 40 SCS, common starting conductor SA, normal contact 127 of relay CLR, conductor 128 to ground at alternate contact 120 of the relay BCR of the cord C that was seized in 45 extending the second call to the operator's position F.

The motor magnet MM² of the switch SCS' is energized over this circuit and steps the wipers 129', 130', 131' and 132' into engagement with the first set of contacts 133', 50 134', 135' and 136'. Upon the first step of the switch wipers off normal, normal contact 124' of the off normal contacts ON³ is moved to its alternate position and a substitute energizing circuit is established for the motor magnet MM², traced from battery through the motor magnet MM², its normal contact 123', alternate contact 124' of the off-normal contacts ON³, conductor 137', normal contact 138', conductor 139' to ground at normal contact 140' of the relay BG³. The motor magnet MM² steps the wipers 129', 130', 55 131' and 132' from one contact set 133', 134', 135' and 136' to the next, and when the wiper 129' engages the grounded contact 133' 60 which is grounded through alternate contact 121 of the relay BCR of the cord C, an energizing circuit is established for the relay BG³ from the said ground at alternate contact 121 of the relay BCR of the cord C that was seized in extending the second connection to the operator at position F, through contact 133', wiper 129', normal contact 145' of the relay SW², conductor 144', normal contact 143' of the relay BG³, through the winding 70 142' of the relay BG³, conductor 141', through the resistance 122' to battery. The circuit through the relay BG³ shunts out the motor magnet MM² of the switch SCS' and prevents further stepping of the wipers of 75 the switch. 80

The closing of alternate contacts 159' and 160' of relay BG³ brings about the energization of the line relay LR⁴, and the line relay LR⁴ in turn closes an energizing circuit for 85 the relay SG'. The closing of alternate contact 140' of relay BG³ closes a circuit for the relay SW² traced from battery through the winding of relay SW², conductor 156', to ground at alternate contact 140' of the relay BG³; the relay SW² then closes a locking circuit for itself through its alternate contact 90 157' to ground at alternate contact 158' of off-normal contacts ON³. The closure of alternate contact 150' of relay BG³ closes a 95 locking circuit for itself traced from battery, conductor 141', through its upper winding 142', its alternate contact 150', through its lower winding 151', wiper 130', contact 134', through the winding of the relay CLR of the 100 cord C that is seized to extend the second connection to ground at alternate contact 155 of the relay BCR of the second cord seized.

The third call having been extended to the operator's position F causes the relays CCR, 105 85 and BCR of the said cord C to energize, and the closing of alternate contact 120 of relay BCR of this third cord C establishes a circuit for the motor magnet MM⁴ of the switch SCS² traced from the ground that 110 was placed on the starting conductor SA, due to the closing of alternate contact 120 of the relay BCR of the third cord, through alternate contact 126 of the switch SCS, over conductor 315, through alternate contact 115 126' of the relay SW² of the switch SCS², over conductor 316, through normal contact 126² of the relay SW³ of the switch SCS², conductor 125², normal contact 124² of the off-normal contacts ON⁴, normal contact 123² 120 of the magnet MM⁴, through the winding of the motor magnet MM⁴, to battery through the resistance 122². The motor magnet MM⁴ steps the wipers 129², 130², 131² and 132² into engagement with the first set of contacts 133², 134², 135² and 136² and the operation of the switch SCS² is the same as described in connection with the switch SCS'. When the wiper 129² engages the grounded wiper 133² 125 due to the closing of alternate contact 121 of 130

the relay BCR of the third cord seized in extending a connection to this operator's position F, it closes an energizing circuit for the relay BG⁴, and the relay BG⁴ upon energization shunts out the motor magnet MM⁴ and prevents further stepping of the wipers of the switch SCS². Relay SW³, relay LR⁵ and relay SG² are also energized.

The fourth call that is extended to the position F selects the fourth cord circuit C associated with the operator's position F, and brings about the energization of the relays CCR, 85 and BCR of the seized cord C, and the closure of alternate contact 120 of the relay BCR of this fourth cord circuit C that is extending a connection to the operator's position F places a ground upon the common starting conductor SA and brings about the energization of the motor magnet MM⁵ of the switch SCS³, the circuit being traced from ground on the starting conductor SA, through alternate contact 126 of the relay SW⁴ of the switch SCS, conductor 315, through alternate contact 126' of the relay SW² of the switch SCS², conductor 316, through alternate contact 126² of the relay SW³ of the switch SCS², over conductor 317, through normal contact 126³ of relay SW⁴, conductor 125³, normal contact 124³ of the off-normal contacts ON⁵, normal contact 123³ of the motor magnet MM⁵, through the winding of the said motor magnet MM⁵, through the resistance 122³ to battery. The motor magnet MM⁵ steps the wipers 129³, 130³, 131³ and 132³ into engagement with the first set of contacts 133³, 134³, 135³, and 136³. Upon the first step of the wipers off normal, the off-normal contacts ON⁵ assume their alternate position, and the closure of alternate contact 124³ closes a substitute energizing circuit for the motor magnet MM⁵ to ground at normal contact 140³ of the relay BG⁵. The motor magnet MM⁵ now steps the wipers from one contact set to the next, and when the wiper 129³ engages the grounded contact 133³, which contact is grounded upon the closure of alternate contact 121 of relay BCR of the fourth cord seized, it brings about the energization of the relay BG⁵, and the relay BG⁵ shunts out the motor magnet MM⁵ and prevents further stepping of the wipers of the switch SCS³. The relay BG⁵, line relay LR⁶, relay SG³ and relay SW⁴ are energized over circuits as previously described.

The first call answered by the operation of the position F has already been described in the previous description in tracing a call from the calling subscriber at the substation A to the called subscriber at the substation D. As soon as the operator's set O is connected to the cord C that has extended the first call to the operator's position F, and after the operator has inserted the plug CP into the multiple jack J' of the called line, the relay BCR is deenergized due to the opening of normal

contact 98 of the sleeve relay SL, and the opening of alternate contact 155 of the relay BCR opens the energizing circuit of the relay BG⁷ of the switch SCS and the relay CLR of the cord C and the closing of normal contact 140 of relay BG⁷ closes an energizing circuit for the release magnet RM² and relay 214. The release magnet RM² withdraws its retaining pawl and allows the switch wipers 129, 130, 131 and 132 to restore to normal. The relay BCR of the cord C when de-energized allows its alternate contact 99 to open and disconnect the resistance 100. The disconnection of this resistance again increases the resistance connected to the common conductor 101 from 750 to 1000 ohms, as there are still three resistances connected in multiple with the conductor 101. This increased resistance permits the relay CA⁹ of the position F to restore as it operates through 750 ohms resistance but releases through a 1000-ohm resistance. The closing of alternate contact 230 of the relay 214 places a releasing battery shunt on the common conductor 321 traced from battery through the alternate contact 320 of the relay 214 over conductor 321, about the windings of relays CA³, CA⁶ and CA⁹ to battery. This shunt does not affect the relay CA, but does restore to normal relay CA⁹, but relays CA³ and CA⁶ are so adjusted that they hold up when the 20-ohm battery shunt is applied. The said shunt exists only momentarily or until the switch SCS restores at which time relay 214 deenergizes its circuit being opened at contacts ON² and the shunt is removed. By the deenergization of BCR one of the resistances 100 has been removed from the circuit, so that when the shunting effect terminates relay CA⁹ does not reenergize because the resistance on wire 101 is now 1000 ohms. The relay CA⁹ restoring to normal, the opening of its alternate contact 113⁹ permits the deenergization of the relay BC⁹ and the relay BC⁹ upon restoration opens its alternate contacts 303⁹ and 306⁹ to open the circuit through the lower windings of the relays PB¹⁰ and PB¹¹ of the positions H and J and the relays PB¹⁰ and B¹¹ are again energized through their upper windings, and the closing of alternate contacts 116¹⁰ and 116¹¹ of the relays PB¹⁰ and PB¹¹ again closes circuits for energizing relays BU associated with positions H and J.

The relay BG⁷ at SCS de-energizes, and the opening of alternate contacts 159 and 160 permits the deenergization of the line relay LR³, and the line relay LR³ deenergizing its alternate contact 166 is opened to permit the deenergization of the relay SG, and the opening of alternate contact 167 of the relay SG opens the energizing circuits of the relay BG⁶ of the switch OS and the said relay restores. The first call having been answered, the second call stored at the position F will now be answered by the operator at the position F.

The relay SG' of the switch SCS' being energized, as before described, ground from alternate contact 168' of said relay SG' extends over conductor 322, through normal contact 5 323 of relay 180 of switch OS, normal contact 324 of the relay BG⁶ of the switch OS, conductor 325, normal contact 326 of the motor magnet MM⁶ of the switch OS, through the winding of the motor magnet MM⁶, through 10 the resistance 184 to battery. The motor magnet MM⁶ now steps the wipers 170, 171, 172 and 173 into engagement with the second set of contacts 174, 175, 176 and 177, and when the wiper 171 engages the contact 175 of the 15 second set, an energizing circuit is again established for the relay BG⁶, traced from battery through the resistance 184, conductor 183 through the winding 182 of the relay BG⁶, normal contact 181 of the said relay BG⁶, normal contact 179 of relay 180, conductor 178, conductor 329 to ground at alternate contact 167' of the relay SG'. The circuit through the relay BG⁶ just described shunts out the motor magnet MM⁶, and the wipers 170, 171, 20 172 and 173 now remain in engagement with the second set of contacts 174, 175, 176 and 177, and the closure of alternate contacts 186 and 187 of the relay BG⁶ now connects the operator's set O to the cord C that was seized 25 in extending the second call to the operator's position F. When the operator of position F inserts the plug of this second cord into the jack of the called line relay BCR of this cord is deenergized thus opening the energizing 30 circuit of the relay BG³ of the switch SCS', and the relay BG³ restoring its normal contact 140' is again closed to complete an energizing circuit for the release magnet RM³. The release magnet RM³ withdrawing its 35 pawl to permit the wipers 129', 130', 131' and 132' to assume their normal position. The relay BCR of the second cord de-energizing its alternate contact 99 is opened, disconnecting the resistance 100 from the common conductor 101 and as there are still two cords connected to the position F two resistances 100 are still connected in multiple with the conductor 101, thus increasing the resistance from 1000 to 1500 ohms. The relay 214' is 40 also energized and the closing of its alternate contact 320' places battery upon the common shunting conductor 321, and the effect of the release shunt placed across the relays CA³ and CA⁶ causes the relay CA⁶ to deenergize, 45 and the opening of the contact 113⁶ permits the relay BC⁶ to de-energize, and the opening of its alternate contacts 303⁶ and 306⁶ permits the relays PB⁷ and PB⁸ of the positions H and J to again energize, as the circuit 50 through their lower windings is opened at the said contacts, to again busy the remaining trunks at the positions H and J.

In regard to the relay 214', it energizes and deenergizes again immediately (as soon as 55 switch SCS' in restoring opens its ON³ con-

tacts) and the shunting battery placed on 321 is connected momentarily only. During the shunting relay CA³ remains operated due to its adjustment. However, relay CA⁶ will not, for reasons previously explained, pull 70 up under these circumstances. It will now be observed that although position F tests idle to incoming calls, there is a double "busy" protection to position H, because relays PB⁷ and PB¹⁰ are both energized. Similarly, relays PB⁸ and PB¹¹ being both energized afford a double "busy" to position J. 75

The operator at the position F now answers a third call. The switch SCS² having selected the third cord C that has been seized in the 80 operator's position F and the relay SG² of the switch SCS² being energized its alternate contact 168² is closed establishing an energizing circuit for the motor magnet MM⁶ of the switch OS, traced from ground at alternate 85 contact 168² over conductor 322, normal contact 323 of the relay 180, normal contact 324 of the relay BG⁶, conductor 325, normal contact 326 of the magnet MM⁶, through the resistance 184 to battery. The magnet MM⁶ 90 now steps the wipers 170, 171, 172 and 173 of the switch OS to the third set of contacts 174, 175, 176 and 177 of the switch OS, and when the wiper 171 engages the contact 175 of the third set, an energizing circuit is established 95 for the relay BG⁶ of the switch OS, traced from ground at alternate contact 167², over conductor 330, contact 175, wiper 171, conductor 178, normal contact 179 of relay 180, normal contact 181 of relay BG⁶, winding 182 100 of the said relay, conductor 183, resistance 184 to battery. The circuit through the relay BG⁶ shunts out the motor magnet MM⁶ and prevents further stepping of the wipers 170, 171, 172 and 173. The closing of alternate contacts 186 and 187 of relay BG⁶ connects the operator's set O to the cord conductors of the cord C that has been seized when the third call has been extended to the operator's position F. When the operator of position F inserts the plug of the third cord into the multiple jack of the called line the relay BCR of this trunk cord restores and opens the energizing circuit of the relay BG⁴ of the switch SCS², and the relay BG⁴ closes its normal contact 140², closing an energizing circuit for the release magnet RM⁴, and the release magnet RM⁴ energizing withdraws the retaining pawl and allows the wipers 129², 130², 131² and 132² to restore to normal. The 110 relay BCR of the third cord trunk deenergizes to open its alternate contact 99 to disconnect the resistance 100 from the common conductor 101, and as there is now only one cord C connected to the position F that is 115 waiting to be extended to a called line the resistance is increased to 3000 ohms. The relay 214² is also energized and the closing of its alternate contact 320² connects battery to the releasing shunt conductor 321 and deener- 120 125 130

gizes the relay CA³. The relay CA³ deenergizing, its alternate contact 113³ is opened to bring about the restoration of the relay BC³, and the opening of alternate contacts 303³ and 306³ of the relay BC³ again permits the energization of the relays PB⁴ and PB⁵ as the circuits through their lower windings are opened at these contacts. Relays PB⁴ and PB⁵ again energizing cause the trunks of their respective positions H and J to be again busied against selection. The relay BG⁴ of the switch SCS² deenergizing its alternate contacts 159² and 160² are opened, permitting the deenergization of the line relay LR⁵, the line relay LR⁵ in turn deenergizing the relay SG². The relay SG² upon deenergization opens the energizing circuit of the relay BG⁶ of the switch OS, and the said relay restores to normal and disconnects the operator's set O from the third cord C. From what has gone before it will be understood that relay 214² only momentarily places the release shunt; also that positions H and J are now "busied" at three places.

The third call having been answered the operator is now connected to the fourth cord that was seized in extending the fourth call to the operator's position F. The closing of alternate contact 168³ of the relay SG³ establishes an energizing circuit for the motor magnet MM⁶ of the switch OS traced from ground at alternate contact 168³ of the relay SG³ of the switch SCS³, over conductor 322 to battery through the winding of the motor magnet MM⁶ of the switch OS over the previously described path. The motor magnet MM⁶ steps the wipers 170, 171, 172 and 173 into engagement with the fourth set of contacts 174, 175, 176 and 177, and the wiper 171 engages the fourth contact 175 of the set, and ground from alternate contact 167³ of relay SG³ establishes a circuit for the relay BG⁶ of the switch OS traced from ground at alternate contact 167³ of the relay SG³, conductor 331, contact 175, wiper 171 to battery through the winding 182 of the relay BG⁶, over a previously described path. This circuit through the relay BG⁶ shunts out the motor magnet MM⁶ and prevents further stepping of the wipers 170, 171, 172 and 173. The relay BG⁶ upon energization closes its alternate contacts 186 and 187 to connect the operator's set O to the fourth cord seized, and when the operator connects the plug of this cord into the multiple jack of the called line the sleeve relay of this cord energizes to open the energizing circuit of the relay BCR of the cord. This opens the energizing circuit of the relay BG⁵ of switch SCS³, and the relay BG⁵ deenergizing its normal contact 140³ is closed thus establishing a circuit for the release magnet RM⁶, and the release magnet RM⁶ energizing withdraws the retaining pawl to permit the wipers 129³, 130³, 131³ and 132³ to restore. The relay BCR of the fourth cord

trunk deenergizes to open its alternate contact 99 to disconnect the resistance 100 from the common conductor 101, and this permits the relay CA of the position F to deenergize, as its circuit is opened at the alternate contact 100 of the deenergized relay BCR. The relay CA upon deenergization opens its alternate contact 113 to cause the deenergization of relay BC, and the relay BC upon deenergization opens its alternate contacts 303 and 306 and permits the relays PB' and PB² at the positions H and J to be energized to hold busy these two positions H and J, so that now positions H and J are "busy" four times as compared to position F.

Now, should another call be extended the call will be extended to the position F and cause the operation of the relay CA as the calls stored at positions H and J have as yet not been answered, and upon the energization of relay CA relay BC will energize but relay PB will not due to its differential construction and due to the energization of relay BC, relays PB' and PB² will also deenergize, but positions H and J will still test busy as the other positions busying relays PB at H and J will still be energized and keep these two positions busy. The position F will, of course, be idle, due to the failure of relay PB to operate, and the next call extended will appear in position F, and this will also be true of the third and fourth calls.

The order in which stored calls were above assumed to be answered, namely, all of position F's calls answered before the operators at H and J answered any of theirs, is, of course, not an order that would be at all likely to occur in actual service conditions, and we adopted it for the purpose of giving a straight ahead explanation of the circuit and switch operation.

The connections of the "busying" apparatus of positions H and J to their trunk circuits and to their respective switches SCS, SCS', etc., and to OS being like those of position F, it will be readily seen that if the operator at position H had been the first to answer one of the twelve calls stored at the three positions F, H and J, then her position (H) would have been the idle one, while the deenergization of the relay BC¹⁰ would unbalance differential relays PB⁹ and PB¹¹, and positions F and J would become "busy".

Assume now that the operator at J next answered a call, her relay CA¹¹ would deenergize and her position would be "idle" as well as position H, position F continuing busy. Now observe that the circuit of the lower or neutralizing winding of relay PB² at F is open both at relay BC¹⁰ (H) and at relay BC¹¹ (J). Thus, position F is twice "idle", as it might for conciseness be expressed. Now, assume that the next operator J answers the second stored call at her position. Then her relays CA⁸ and BC⁸ will deenergize with

obvious results as to relay PB⁸. The lower or neutralizing winding of relay PB⁷ at H will be open at contact of relay BC⁸ at J. Hence, PB⁷ energizes to "busy" position H. In this status it will be noted that position F is twice "busy" towards position J and once "busy" towards position H, while H is once "busy" towards position J. Further detail is considered superfluous it being now apparent that the organization governs itself on the principle of selectivity and seeks automatically and continuously, as calls come in and are disposed of, to keep an even number before each operator of the group.

The switch OS which connects the operator's set O to the cord conductors is a five-point switch, and from the previous description, it is remembered that the wipers 170, 171, 172 and 173 were left in engagement with the fourth set of contacts. Now when another call is extended to the position F, ground over conductor 322 will close an energizing circuit for the motor magnet MM⁶ over a circuit as previously described to step the wipers 170, 171, 172 and 173 into engagement with the fifth set of contacts 174, 175, 176 and 177, and when the wipers 170 and 171 engage the contacts 174 and 175, which are permanently grounded, a circuit is established for the relay BG⁶, traced from battery through the resistance 184, conductor 183, winding 182 of relay BG⁶, normal contacts 181 and 179 of relays BG⁶ and 180 to ground at contact 175 engaged by wiper 171. The ground at contact 174 which is now engaged by wiper 170 closes an energizing circuit for relay 180 from battery through the winding of relay 180 to ground at contact 174 engaged by wiper 170. Relay 180 upon energization closes its alternate contact 335 to close a locking circuit for itself, traced from battery through relay 180, its alternate contact 335 to ground at alternate contact 336 of off-normal contacts ON⁶, which assumed their alternate position upon the first step of the wipers of the switch OS off normal. The opening of normal contact 179 of relay 180 opens the energizing circuit of relay BG⁶, and relay BG⁶ upon restoration closes its normal contact 337, establishing an energizing circuit for the release magnet RM⁶, traced from battery through the winding of magnet RM⁶, alternate contact 338 of relay 180, to ground at normal contact 337 of relay BG⁶. The release magnet RM⁶ upon energization withdraws the retaining pawl and allows the wipers 170, 171, 172 and 173 to restore to their normal position to again engage the first set of contacts 174, 175, 176 and 177.

The wipers upon restoration bring about the restoration of the off normal contacts ON⁶, and the opening of alternate contact 336 of contacts ON⁶ opens the energizing circuits of the relay 180 and release magnet

RM⁶ so as to again start selecting to connect the operator's set O to the cord C to which a call has been extended.

While I have illustrated and described a particular embodiment of my invention, it is to be understood that changes and modifications will readily suggest themselves to those skilled in the art and I therefore aim to cover all such changes and modifications as come within the spirit and scope of the appended claims.

Having described my invention, what I claim as new and desire to secure by United States Letters Patent, is:

1. A telephone system including telephone lines, operator's cord circuits and automatic non-numerical switches for interconnecting said lines as calling and called lines, storing means for storing calls before the operator's position in the order initiated, an operator's set, automatic means including automatic switches for connecting said operator's set to said cord circuits and for permitting the operator to handle the calls only in the order initiated and stored, signalling means individual to cord circuits for indicating stored calls, a second signal individual to said cords for indicating the cord circuit to which the operator's set is connected, and test means associated with said operator's set including revertive busy test means to indicate when a party is calling a party connected to the same line.

2. In a telephone system comprising telephone lines, operators' positions and groups of cord circuits for each of said operators' positions, non-numerical switches associated with said lines for selecting any of said lines as calling lines, other non-numerical switches for extending said calling lines only to cord circuits at idle operators' positions, call storing means and position busying means for each of said operators' positions, said storing means operable upon the selection of any one of said cords in an operator's position by said second non-numerical switches to cause the operation of said busying means to render the selected position busy against selection, an operator's telephone set for each operator's position, automatic means for connecting the operator's telephone set to the selected cord in said idle operator's position, indicating means individual to each cord circuit operating to apprise the operator of calls stored at the position, and a second signal individual to each cord circuit to indicate the cord circuit to which her set has been connected, and test means associated with said operator's set including revertive busy test means to indicate when a party is calling a party connected to the same line.

3. In a telephone system comprising telephone lines, operators' positions and a plurality of cord circuits associated with each operator's position, means for seizing said

- lines as calling lines, and means for extending said seized lines only to cord circuits at idle operators' positions, call storing means for each operator's position comprising a plurality of units for storing calls in the same order in which the calls are extended to said operators' circuits, a group of sequence switches cooperating with said storing means and being the same in number as the number 10 of units of said storing means, such a group of switches being associated with each operator's position, an operator's telephone set for each operator's position, an operator's selecting switch for each operator's position and 15 common to the group of sequence switches thereat and operable by one of said sequence switches for connecting the operator's set to the seized cord, a signal individual to each cord circuit and adapted to light when connection is made with a cord of an idle operator's position to give the operator a distinctive indication that a call is stored at her position, a second signal individual to each cord circuit operator to indicate the cord 20 circuit to which her set has been connected, and test means associated with said operator's set including revertive busy test means to indicate when a party is calling a party connected to the same line.
- 30 4. In a telephone system comprising telephone lines, operator's positions at the exchange switchboard including a plurality of cord circuits for each of said operators' positions, groups of switches associated with 35 said lines for selecting the said lines as calling lines, other groups of switches for extending said seized lines only to cord circuits at idle operators' positions, storing means and position busying means for each operator's 40 position, a plurality of storing units for each operator's position for storing calls in the same order in which the calls are extended to said operators' circuits, a group of sequence switches the same in number as the number 45 of storing units of an operator's position, an operator's telephone set for each operator's telephone position, an operator's selecting switch for each operator's position and common to each group of sequence switches, and means operable in said sequence switches to cause said operator's switch to function to connect the operator's set of said idle position to the seized cord, a lamp signal individual to each cord circuit to indicate a stored call at the seized operator's position, a second signal individual to each cord, means actuated in the seized cord when the operator's set is connected thereto to cause said second lamp to light to indicate the cord circuit to which her telephone set is connected, and subscriber controlled means for removing the busy indication in lines connected for conversational circuit.
- 50 5. A telephone system including telephone lines, an operator's position, a group of cord 55 circuits for said operator's position, automatic switches common to said lines and arranged in pairs for selecting said lines as calling lines and for extending the same to idle cord circuits of said group of cord circuits, means for storing the extension of said calling lines to said operator's position, an operator's telephone set for said position, automatic 60 means including nonnumerical switches for connecting said operator's telephone set to said selected idle cord circuits, whereby the operator is enabled to extend the calling lines to desired called lines, and test means associated with said operator's set including revertive busy test means to indicate when a party is calling a party connected to the same line.
- 65 6. A telephone system including telephone lines, an operator's position, a group of cord circuits for said operator's position, automatic switches common to said lines and arranged in pairs for selecting said lines as calling lines and for extending the same to idle cord circuits of said group of cord circuits, means for storing the extension of said calling lines to said operator's position, an operator's telephone set for said position, automatic 70 means including nonnumerical switches for connecting said operator's telephone set to and from said selected idle cord circuits in the same chronological order in which said cords are selected, whereby the operator is enabled to extend the calling lines to the desired called lines, in the order the calls are initiated, a pair of signals for each cord circuit, one of said signals indicating to the operator the cord circuit selected and the other lamp indicating the particular cord circuit to which her telephone set is connected, and test means associated with said operator's set including revertive busy test means to indicate when a party is calling a party connected to the same line.
- 75 7. A telephone system including telephone lines, an operator's position, a group of cord circuits for said operator's position, automatic switches common to said lines and arranged in pairs for selecting said lines as calling lines and for extending the same to idle cord circuits of said group of cord circuits, means for storing the extension of said calling lines to said operator's position, an operator's telephone set for said position, automatic 80 means including nonnumerical switches for connecting said operator's telephone set to and from said selected idle cord circuits in the same chronological order in which said cords are selected, whereby the operator is enabled to extend the calling lines to the desired called lines, in the order the calls are initiated, a pair of signals for each cord circuit, one of said signals indicating to the operator the cord circuit selected and the other lamp indicating the particular cord circuit to which her telephone set is connected, and test means associated with said operator's set including revertive busy test means to indicate when a party is calling a party connected to the same line.
- 85 8. A telephone system including telephone lines, an operator's position, a group of cord circuits for said operator's position, automatic switches common to said lines and arranged in pairs for selecting said lines as calling lines and for extending the same to idle cord circuits of said group of cord circuits, means for storing the extension of said calling lines to said operator's position, an operator's telephone set for said position, automatic 90 means including nonnumerical switches for connecting said operator's telephone set to and from said selected idle cord circuits in the same chronological order in which said cords are selected, whereby the operator is enabled to extend the calling lines to the desired called lines, in the order the calls are initiated, a pair of signals for each cord circuit, one of said signals indicating to the operator the cord circuit selected and the other lamp indicating the particular cord circuit to which her telephone set is connected, and test means associated with said operator's set including revertive busy test means to indicate when a party is calling a party connected to the same line.
- 95 9. A telephone system including telephone lines, an operator's position, a group of cord circuits for said operator's position, automatic switches common to said lines and arranged in pairs for selecting said lines as calling lines and for extending the same to idle cord circuits of said group of cord circuits, means for storing the extension of said calling lines to said operator's position, an operator's telephone set for said position, automatic 100 means including nonnumerical switches for connecting said operator's telephone set to and from said selected idle cord circuits, whereby the operator is enabled to extend the calling lines to desired called lines, and test means associated with said operator's set including revertive busy test means to indicate when a party is calling a party connected to the same line.
- 105 10. A telephone system including telephone lines, an operator's position, a group of cord circuits for said operator's position, automatic switches common to said lines and arranged in pairs for selecting said lines as calling lines and for extending the same to idle cord circuits of said group of cord circuits, means for storing the extension of said calling lines to said operator's position, an operator's telephone set for said position, automatic 110 means including nonnumerical switches for connecting said operator's telephone set to and from said selected idle cord circuits, whereby the operator is enabled to extend the calling lines to desired called lines, a pair of signals for each cord circuit, one of said signals indicating to the operator the cord circuit selected, said other signal indicating the particular cord circuit to which her telephone set is connected, and test means associated with said operator's set including revertive busy test means to indicate when a party is calling a party connected to the same line.
- 115 11. A telephone system including telephone lines, an operator's position, a group of cord circuits for said operator's position, automatic switches common to said lines and arranged in pairs for selecting said lines as calling lines and for extending the same to idle cord circuits of said group of cord circuits, means for storing the extension of said calling lines to said operator's position, an operator's telephone set for said position, automatic 120 means including nonnumerical switches for connecting said operator's telephone set to and from said selected idle cord circuits, whereby the operator is enabled to extend the calling lines to desired called lines, a pair of signals for each cord circuit, one of said signals indicating to the operator the cord circuit selected, said other signal indicating the particular cord circuit to which her telephone set is connected, and test means associated with said operator's set including revertive busy test means to indicate when a party is calling a party connected to the same line.
- 125 12. A telephone system including telephone lines, an operator's position, a group of cord circuits for said operator's position, automatic switches common to said lines and arranged in pairs for selecting said lines as calling lines and for extending the same to idle cord circuits of said group of cord circuits, means for storing the extension of said calling lines to said operator's position, an operator's telephone set for said position, automatic 130 means including nonnumerical switches for connecting said operator's telephone set to and from said selected idle cord circuits, whereby the operator is enabled to extend the calling lines to desired called lines, a pair of signals for each cord circuit, one of said signals indicating to the operator the cord circuit selected, said other signal indicating the particular cord circuit to which her telephone set is connected, and test means associated with said operator's set including revertive busy test means to indicate when a party is calling a party connected to the same line.

busy test means to indicate when a party is calling a party connected to the same line.

8. A telephone system including a calling subscriber's line, a link circuit for establishing a connection with a called line, means controlled by said calling subscriber for connecting said link circuit to said calling line, a signal operative upon connection of said calling line to said link circuit, an operator's telephone, a signal operative upon connection of said telephone to said link circuit, and test means associated with said operator's telephone including revertive busy test means to indicate when a party is calling a party connected to the same line.

9. A telephone system including a calling subscriber's line, a link circuit for establishing a connection with a called line, means controlled by said calling subscriber for connecting said link circuit to said calling line, a signal operative upon connection of said calling line to said link circuit, an operator's telephone, a signal operable upon connection of said telephone to said link circuit, and revertive busy test means operative when said link circuit tests said calling subscriber's line.

10. A telephone system including a calling subscriber's line, a link circuit for establishing a connection with a called line, an operator's set adapted to be automatically connected to said link circuit, means controlled by said calling subscriber for connecting said link circuit to said calling line, a signal operative upon connection of said calling line to said link circuit to indicate to the operator that a call has been made, busy test means for said link circuit for testing said calling subscriber's line, means associated with said operator's set including a revertive busy tone to indicate when a party is calling a party connected to the same line, and means for preventing effective connection of said link circuit with the busy called subscriber's line if said link circuit is inadvertently connected thereto.

11. A telephone system including a calling subscriber's line, a link circuit for establishing a connection with a called line, means controlled by said calling subscriber for connecting said link circuit to said calling line, a signal operative upon connection of said calling line to said link circuit, an operator's telephone, and a signal operative upon connection of said telephone to said link circuit, said second signal being effaced when connection is made with said called line and said first signal being effaced when the called line is being signalled, and test means associated with said operator's telephone including revertive busy test means to indicate when a party is calling a party connected to the same line.

12. A telephone system including calling

subscribers' lines, link circuits for connections with called lines, means controlled over calling subscriber's lines for automatically connecting said link circuits to said calling subscriber's lines, signals operative to designate link circuits connected to calling subscribers' lines, operators' telephone sets, signals operative to designate which of said link circuits said operators' telephone sets are connected to, and test means associated with said operator's telephone set including revertive busy test means to indicate when a party is calling a party connected to the same line.

13. A telephone system including calling subscribers' lines, link circuits for connections with called lines, means controlled over said calling subscribers' lines for automatically connecting said link circuits to said calling subscribers' lines, signals operative to designate link circuits connected to calling subscribers' lines, operators' telephone sets, signals operative to designate which of said link circuits said operators' telephone sets are connected to, means for effacing said first signals when the called subscribers are signalled, means for effacing said second signals when connections are made with called subscribers' lines, and test means associated with said operator's telephone set including revertive busy test means to indicate when a party is calling a party connected to the same line.

14. A telephone system including calling subscribers' lines, link circuits for connections with called lines, means controlled over said calling subscriber's lines for automatically connecting said link circuits to said calling subscribers' lines, signals operative to designate link circuits connected to calling subscribers' lines, operators' telephone sets, signals operative to designate which of said link circuits said operators' telephone sets are connected to, means for effacing said first signals when the called subscribers are signalled, and means for effacing said second signal when connections are made with called subscribers' lines, and subscriber controlled means for removing the busy indication in lines connected for conversational circuit.

15. A telephone system including calling subscribers' lines, link circuits for connections with called lines, means controlled over said calling subscribers' lines for automatically connecting said link circuits to said calling subscribers' lines, signals operative to designate link circuits connected to calling subscribers' lines, operators' telephone sets, signals operative to designate which of said link circuits said operators' telephone sets are connected to, means for effacing said first signals when the called subscribers are signalled, means for effacing said second signals when connections are made with called

subscribers' lines, subscriber controlled means for removing the busy indication from lines connected for conversational circuit, means controlled by calling subscribers for releasing part of the apparatus used in said connections, and means controlled by the called subscribers for releasing other parts of said apparatus used in said connections.

16. A telephone system including an operator's position, automatic means for extending calls to said position, an operator's set, automatic means to connect said operator's set for answering the calls extended to said position in the order in which they were received and test means including revertive busy means to indicate when a party is calling a party connected to the same line.

17. A telephone system including an operator's position, automatic means for extending calls to said position, an operator's set, automatic means to connect said operator's set for answering the calls extended to said position in the order in which they were received and test means associated with said operator's set to indicate when a party is calling a party connected to the same line.

18. A telephone system including an operator's position, automatic means for extending calls to said position, an operator's set, automatic means for connecting said operator's set to answer the calls extended to said position in the order in which they were received and test means associated with said operator's set including a revertive busy tone to indicate when a party is calling a party connected to the same line.

19. An automatic distributing system for telephone exchanges including single plug cord circuits at an operator's position, automatic selecting switches to connect subscribers' lines with idle cord circuits, means for storing calls at said operator's position, operator sequence switches for said position to automatically connect her talking set with the selected cord circuits successively and in the same order in which the stored calls appeared at the operator's position and test

means for indicating when a party is calling a party connected to the same line.

20. An automatic distributing system for 50 telephone exchanges including a single plug cord circuit at an operator's position, automatic selecting switches to connect subscribers' lines with idle cord circuits, means for storing calls at said operator's position, operator sequence switches for said position to automatically connect her talking set with the selected cord circuits successively and in the same order in which the stored calls appeared at the operator's position and test 55 means associated with said operator's set including a revertive busy tone for indicating when a party is calling a party connected to the same line.

21. In an automatic distributing system, 65 means for automatically assigning time preferences for incoming calls according to priority of their coming in, an operator's set, means for automatically connecting said operator's set to the circuits on which the calls 70 come in according to priority, signalling means for said circuits operative upon the connection of the incoming calls to the said circuits and a second signal operative upon the connection of said operator's set to said 75 circuit.

22. A telephone system including a plurality of operator's positions, operators' sets, means for extending and storing calls at said operators' positions and for equalizing the 80 number of calls stored at the different operators' positions, means associated with said operators' positions to connect said operators' sets for answering the calls stored at the different operators' positions in the order in 85 which they were received, and test means associated with said operator's set including a revertive busy tone operative when a party is calling a party connected to the same line.

Signed by me at Chicago, in the county of 90 Cook and State of Illinois, this 18th day of September, 1926.

MICHAEL B. STAZAK.
